MORTIMER N. GRIFFIN AND RUGAR E. GEORGE, OF ROME, GEORGIA.

QUICK-LIFT PUMP.

1,417,317.

Specification of Letters Patent. Patented May 23, 1922.

Application filed June 26, 1919. Serial No. 306,905.

To all whom it may concern:

Be it known that we, MORTIMER N. GRIFFIN and RUGAR E. GEORGE, citizens of the United States, residing at Rome, in the county of Floyd and State of Georgia, have invented certain new and useful Improvements in Quick-Lift Pumps, of which the following is a specification.

Our invention relates to an improvement 10 in a quick lift pump, with automatic cut-out, and adapted more particularly for use in connection with the regular pumps on hydraulic direct lift presses, and the present invention is, in reality, an auxiliary pump 15 operated in connection with the two high pressure pumps of such a press.

The present invention comprises a pump 20 with a double plunger, the inner of which takes the initial power, and the other of which handles liquid in connection with a spring which controls the pressure within the outer plunger, said spring bearing on the bottom of the inner plunger, so that when pressure has reached the maximum 25 strength of the spring, the movement of the outer plunger will be stopped, and the inner plunger will continue to travel, thereby compressing and expanding the spring at each stroke of the inner plunger, thus making 30 an automatic cut-out for the pump without any cessation in the movement of the initial power.

In the accompanying drawings:

Fig. 1 is a view in perspective of the end 35 of a press showing our improvement attached thereto;

Fig. 2 is an enlarged view in side elevation; and

Fig. 3 is a section.

A, represents a push-rod connection which 40 extends from the center eccentric 1 on the drive-shaft 2. B is an auxiliary plunger connected to the push-rod by a pin 3 extending through the hole 4. C, is the main plunger, and D, is a pump-barrel. The auxiliary plunger B is fitted within the bore of the outer plunger C, as clearly shown in Fig. 45 3, the inner plunger B taking the initial power while the outer plunger C handles the liquid in the barrel D. G, is the suction line leading from the tank.

A spring 6 located in the bore of the outer plunger C bears against the bottom of the latter, and the inner end when plunger B is 50 as shown in Fig. 3, and when pressure has reached the maximum strength of this

spring the outer plunger C will strike the stop-bracket E projecting outwardly from the press 8 and stop moving, as shown in Fig. 2, the collar 9 being secured on the upper end of the outer plunger C for that purpose, and the inner plunger B will continue to travel, it being provided with the grooves 10. These grooves extend longitudinally thereof, and into them the pins 11 extend from the collar 9, they being held in position by the set-screws 12, as shown in Fig. 3. This continued travel of the inner plunger results in the compression and expansion of the spring 6 at each stroke of the inner plunger, thereby making an automatic cut-out for the pump without stopping the movement of the initial power.

F, represents a check-valve located in the pipe 13 leading from the barrel D. H is the 75 discharge pipe line (see Fig. 1) from the auxiliary pump, as well as from two high pressure pumps I which are connected to the discharge pipe H by the pipes K.

The action of the pump is as follows:— 80 Plunger C is preferably bored out to a depth of about ten inches, and the coil-spring 6 inserted therein, and between its bottom and the end of the inner plunger B is of sufficient strength to withstand a pressure of sixty 85 pounds per square inch on plunger C. When the pressure on plunger C increases to a point above sixty pounds, the plunger will stop at the top of its stroke and bear against stop-bracket E, and remain there while 90 plunger B continues to travel, compressing and releasing spring 6 at each stroke. This makes a positive cut-out for the low pressure pump and makes it unnecessary to employ any troublesome automatic valves, the 95 idea being that all three pumps will handle the liquid until the pressure in the cylinder of the press has reached a maximum of sixty pounds per square inch, when the plunger C will stop at the top of its stroke, thereby 100 stopping the action of this pump, and the high-pressure check-valve marked F will hold the liquid pumped out of the pump-barrel D, and the two smaller pumps I will 105 build up the pressure necessary for the final operation of the press.

We claim:

1. In a hydraulic press, the combination with high pressure pumps, of an auxiliary pump comprising an inner and outer plunger having a spring interposed therebetween, and a barrel to the bore of which the outer

plunger is fitted, a stop for the outer plunger, a check-valve, and pipe lines for the several pumps.

2. In a hydraulic press, the combination 5 of high-pressure and auxiliary pumps, pipelines therefor, the auxiliary pump comprising a barrel and an inner and outer plunger with interposed spring, the outer of which plunger is fitted to the bore of the barrel, 10 means for limiting the stroke of the outer plunger, and a check-valve connected with the barrel.

3. The combination with a hydraulic press, and pumps and pipes therefor, of an 15 auxiliary pump, comprising a barrel and an inner and outer plunger with an interposed spring, a discharge pipe line connecting all three pumps, a check-valve in the pipe leading from the auxiliary pump, and means for 20 stopping the outer plunger in the auxiliary pump when the pressure in the cylinder of the press has reached a certain point, thereby stopping the action of the auxiliary pump, the check-valve holding the liquid 25 pumped out of the pump, while the high-pressure pumps will continue to build up the pressure necessary for the final operation of the press.

4. The combination with a hydraulic press, of two high-pressure pumps and an auxiliary pump, the auxiliary pump having an inner and outer plunger fitted to operate one within the other, a barrel in which the outer plunger operates, a spring interposed between the inner and outer plunger, and means for stopping the outer plunger when a predetermined pressure has been reached in the cylinder of the press.

5. The combination with a hydraulic press, and a shaft having a plurality of eccentrics thereon, of high-pressure pumps and an auxiliary pump all operated from the plurality of eccentrics on the shaft, the auxiliary pump having an inner and outer plunger fitted to operate one within the other, a barrel in which the outer plunger operates, a spring interposed between the inner and outer plunger, and means for stopping the outer plunger when a predetermined pressure has been reached in the cylinder of the press.

In testimony whereof we affix our signatures.

MORTIMER N. GRIFFIN.
RUGAR E. GEORGE.
